BATH CABINET

Filed May 31, 1929

UNITED STATES PATENT OFFICE

ANDREW RUSATZ, OF NORTHAMPTON, PENNSYLVANIA, ASSIGNOR OF ONE-HALF TO
JOHN YURASITS, OF NORTHAMPTON, PENNSYLVANIA

BATH CABINET

Application filed May 31, 1929. Serial No. 367,280.

This invention relates to a bath cabinet and its object is to provide in a cabinet of this character the various elements required for bathing, all so arranged and disposed as to be completely concealed when not in use, but with means to make them immediately available upon the opening of the doors of the said cabinet.

A further object is a casing structure so built as to resemble in appearance an ordinary article of furniture such as a book case or the like.

Another object is a co-ordinated mechanism by which protective curtains may be brought into position to obscure the interior of the cabinet, and a seat element placed in position for use when the doors of the said cabinet are opened.

Other objects are, means for heating a water supply and for tempering the same with cold water.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a front view of the cabinet with the doors closed.

Fig. 2 is an enlarged perspective view with the doors open and the curtains shielding the interior of the cabinet.

Fig. 3 is a front view of the cabinet with the doors open and the curtains and their supporting rod removed.

Fig. 4 is a section on the line 4—4 of Fig. 3.

Fig. 5 is a plan section on the line 5—5 of Fig. 4.

Fig. 6 is an enlarged fragmentary detail view of the curtain projecting mechanism at one end of the cabinet.

Fig. 7 is a fragmentary section on the line 7—7 of Fig. 6.

Fig. 8 is an enlarged fragmentary section showing the curtain material and the waterproof lining of the same.

The invention may be described as follows.

A cabinet 10 is provided with doors 11. The cabinet may be of any design and may be constructed of any suitable material. A tub 12 is mounted within the cabinet and a reservoir tank 13 is preferably positioned near to the top thereof.

This reservoir is connected to the heating element 14 by the pipe 15 and to a tub faucet 16 by the pipe 17. A cold water pipe 18 leads to the opposite faucet 19. A drain pipe 20 serves to carry off the used water from the tub. The heating element may be of any type desired, such as gas, electric, or otherwise.

The curtains 22 are preferably constructed with an outer covering or fabric 23, and an inner lining 24 which may be of rubberized cloth or any waterproof material. This is shown in Fig. 8. These curtains are slidably suspended on a rod 25 and this rod has side members 26 which merge into slide elements 27. These elements may be best understood on reference to Figs. 6 and 7 of the drawings. The slide elements are supported by the guides 28. At the ends of the slide elements are lugs 29 and to these are pivotally secured the pull levers 30.

These levers are secured by pivots to the door lugs 31. Referring to Fig. 6 it will be seen that when the doors are opened the levers will draw the slide elements forward thus projecting the curtain rod outward into its forward position as indicated by the dotted lines 35. This places the curtains at a distance from the interior of the cabinet and leaves ample room for a person to use the tub and the adjacent seat 36 which is seen in the several open views.

The seat 36 is foldably mounted near to the tub on the base members 37, and is held in operative position by the slide brackets 38 which have brace members 39 slidably connected to the vertical rods 40. Referring to Fig. 5, a side lever 41 is seen which operates the seat 36 and raises same to its vertical, folded position as indicated by the dotted lines 42 seen in Fig. 4. This lever is actuated by the cable 43 acting over the pulley 44 and affixed to the lug 29 of the curtain projecting elements. The seat and the cur-

tains are simultaneously moved into operative positions by the coordinated mechanism as previously described and are withdrawn and folded within the cabinet upon the closing of the doors thereof.

While the cabinet as shown is a portable structure, the apparatus therein contained may be built into a room or closet if desired, and it is further understood that such other minor changes may be made therein as may come within the spirit and scope of the appended claims without the relinquishment of any of the inherent rights of the invention.

Having thus described my invention, what I claim as new, and desire to secure by United States Letters Patent is:—

1. In combination with a closet having hinged doors, horizontal guides secured within the closet, a rod having a transverse portion for supporting a curtain and side arms slidably secured on the guides, pull levers pivotally secured at their front ends to the doors and at their rear ends to the guides for projecting the curtain outward upon opening of the doors.
2. In combination with a closet having hinged doors, horizontal guides secured within the closet, a rod having a transverse portion for supporting a curtain and side arms merging into slide elements secured on the guides, pull levers pivotally secured at their front ends to the doors and at their rear ends to the guides for projecting the curtain outward upon opening of the doors.
3. In testimony whereof I have affixed my signature.

ANDREW RUSATZ.
